UNITED STATES PATENT OFFICE.

HENRY L. BARTON, OF GARY, INDIANA.

PLOW.

1,292,232.

Specification of Letters Patent.

Patented Jan. 21, 1919.

Original application filed October 11, 1915, Serial No. 55,168. Divided and this application filed February 18, 1916. Serial No. 79,117.

To all whom it may concern:

Be it known that I, HENRY L. BARTON, a citizen of the United States, and a resident of the city of Gary, county of Lake and 5 State of Indiana, have invented certain new and useful Improvements in Plows, of which the following is a specification.

My invention relates to improvements in plows especially adapted for use in grading machines and has for its object the provision of an improved construction of this character which is simple and efficient in use, the subject matter of the present application constituting in part that disclosed in 10 my prior application Serial #55,168, filed October 11th, 1915, and being divided therefrom.

The invention consists in the combinations and arrangements of parts hereinafter described and claimed.

The invention will be best understood by reference to the accompanying drawings forming a part of this specification, and in which—

25 Figure 1 is a top plan view of a grading machine equipped with a plow embodying my present invention.

Fig. 2, a side view of the same shown partially in section,

30 Fig. 3, an enlarged detail view of a pointed shoe employed in the construction,

Fig. 4, an enlarged section taken on line 4—4 of Fig. 2,

Fig. 5, a detail view of an adjustable cross 35 bar employed in the construction.

The preferred form of construction as 40 illustrated in the drawings comprises a frame 6 mounted on front wheels 7 and rear wheels 8. The front wheels 7 are loosely mounted in the ordinary manner on the front axle 9 and the rear wheels 8 are fixed to a rear axle 10 which is thus caused to rotate with the wheels. A gear 11 is fixed to the front axle 9 and meshes with a pin-

45 ion 12 at the lower end of a shaft 13 which is provided with a handle 14 for steering the machine. A plow beam 15 is secured at its rear end to axle 10, said plow beam being provided with a knuckle joint 16 and a 50 swivel joint 17 by means of which the beam may be swung vertically or laterally or may be twisted on a horizontal longitudinal axis. At its front end the beam 15 carries an ordinary plow share 18 and a stop chain 19 which serves to limit the downward swing of the

plow beam 15 and the depth of cut of the plow. An adjusting chain 20 is also secured to the front of beam 15 and is connected with a windlass 21 by means of which plow 18 may be vertically adjusted or may be entirely raised from contact with the ground, as will be readily understood.

55 A transverse adjusting bar 22 is pivotally connected at 23 to the beam 15 and extends transversely across the frame 6 passing 60 slidably through a bracket 24 suspended on said frame. Bar 22 is provided with a plurality of holes 25 adapted to receive pins or bolts 26 and by means of which the lateral position of the bar may be adjusted in the 65 bracket 24 to control or adjust the lateral position of the plow 18. A brace 27 is pivotally connected at 28 with the plow beam 15 and is adjustably secured to the cross bar 22 by means of pins or bolts 29 passing 70 through perforations 30 as indicated. By this arrangement, the plow 18 may be tilted 75 or angularly adjusted as desired.

75 A pointed shoe 31 is secured to the lower end of a bracket 32 depending from the forward end of plow beam 15 in position to immediately precede the plow 18 and serve as a means for breaking up the earth ahead of said plow to facilitate the action thereof. Pointed shoe 31 is provided with a socket 80 31' adapted to receive the lower end of the bracket 32 and with a lip 33 adapted to engage in a corresponding recess in said bracket, the two being secured together by means of bolts 34 passing therethrough as 85 shown.

85 A scraper or scoop 35 is arranged at the lower end of an elevator 36 leading to a discharge elevator 37 thereon, said scraper, elevator and conveyer being arranged to co-operate with the plow 18 as will be readily understood. The scraper, elevator and conveyer constitute the subject matter of my prior application Serial No. 55,168, filed 90 October 11th, 1915, referred to above and require no further description herewith.

95 A draft bar 38 is pivotally connected with a draft clevis 39 having a bolt and slot connection with the draft tongue 40 which is connected to the front axle 9 in the usual 100 manner and by means of which the machine may be drawn by a traction engine or other suitable means. At its rear end the draft bar 38 is connected by means of a chain 41 105 with the bar 22 and by means of chains 42 110 with the beam 15.

with the lower portion of the elevator 36, so that the draft power will be directly transmitted to both the plow and the scoop.

By this arrangement it will be observed that the plow may be readily adjusted in 5 different positions on the frame of the machine to meet different requirements and secured in such positions. The specific arrangement disclosed constitutes a simple and efficient one for the purpose.

10 While I have illustrated and described the preferred form of construction for carrying my invention into effect, this is capable of variation and modification without departing from the spirit of the invention. I, therefore, do not wish to be limited to the 15 precise details of construction set forth, but desire to avail myself of such variations and modifications as come within the scope of the 20 appended claims.

25 Having described my invention what I claim as new and desire to secure by Letters Patent is:

1. A grading machine comprising a 25 wheeled frame having a rear axle; a plow beam mounted on said rear axle and extending forwardly therefrom; a knuckle joint on said rear axle permitting of lateral and vertical swinging of said plow beam; a swiveled joint for said plow beam permitting of 30 tilting thereof; a plow share on said plow beam; and means for securing said plow beam in different lateral and tilted positions, substantially as described.

35 2. A grading machine comprising a

wheeled frame having a rear axle; a plow beam mounted on said rear axle and extending forwardly therefrom; a knuckle joint on said rear axle permitting of lateral and vertical swinging of said plow beam; a swiveled joint for said plow beam permitting of 40 tilting thereof; a plow share on said plow beam; means for limiting the downward swing of said plow beam; and adjustable means for securing said plow beam in different lateral and tilted positions, substantially 45 as described.

3. A grading machine comprising a wheeled frame having a rear axle; a plow beam mounted on said rear axle; a knuckle joint on said rear axle permitting of lateral and vertical swinging thereof; a swiveled joint for said plow beam permitting of 50 tilting thereof; a plow share on said plow beam; means for limiting the downward swing of 55 said plow beam; a cross bar pivotally connected with said plow beam and traversing the frame of the machine; means for securing said cross bar in different lateral positions; and a brace pivotally connected with 60 said plow beam and adjustably connected with said cross bar, substantially as described.

In testimony whereof I have signed my name to this specification in the presence of 65 two subscribing witnesses.

HENRY L. BARTON.
